UNITED STATES PATENT OFFICE.

HARRY W. MANNING, OF PORTLAND, OREGON.

OIL-BURNER.

1,389,207.

Specification of Letters Patent. Patented Aug. 30, 1921.

Application filed December 15, 1919. Serial No. 345,157.

To all whom it may concern:

Be it known that I, HARRY W. MANNING, a citizen of the United States, and a resident of Portland, county of Multnomah, State of Oregon, have invented a new and useful Improvement in Oil-Burners, of which the following is a specification.

My invention relates to fuel oil burners intended for being installed in the fire-box 10 of a stove or other heating apparatus.

The following are the particular features of my invention:

1. I provide my burner with a burner-head which is adapted for being arranged to 15 burn either with a circumferential flame, or with a vertical flame; the latter being desirable when a cooking utensil is to be quickly heated by direct application of the flame, instead of first having to heat up the 20 entire stove.

2. The gas generator of my burner is especially adapted for speeding up the gasifying of the fuel oil. To this end my generator preferably consists of a coil of horizontal 25 pipes vertically stacked and

3. I provide an efficient heating element for such generator, such element tending to distribute the flame along the entire length of the generator so as to more efficiently 30 heat the latter.

The above features of my invention are illustrated in the accompanying drawings, the description of which, hereinafter contained, fully discloses both the principles of 35 construction and operation of my invention.

My invention also includes incidental features hereinafter fully described.

In said drawings Figure 1 is a top view of my improved burner, the same being 40 shown as provided with two burner-heads, and the dome, or cover of one thereof is removed, as would be the case where the flame is to issue vertically from the burner-head for direct application to the cooking 45 utensil;

Fig. 2 is a side elevation of the same burner arranged in the same manner as illustrated in Fig. 2;

Fig. 3 is a section of the burner-head on 50 the line 3—3 of Fig. 1, looking in the direction indicated by the arrow;

Fig. 4 is a larger-scaled section approximately taken on the line 4—4 of Fig. 2,

looking in the direction indicated by the arrow;

55

Fig. 5 is a larger-scaled perspective sectional detail of the slotted plate by which the open top of the hollow body of the burner-head is closed;

Fig. 6 is a top view of the heating element 60 of the gas generator; and

Fig. 7 is a plan or top view of the bottom plate of said heating element.

My burner consists of a tubular body or conduit *a*, provided with an air-and-gas mixing chamber *b* with which is connected the gas generator *c*. The latter consists of a coil of horizontal pipes vertically stacked. The generator is connected by a hollow wire *d* with the tank (not shown) in which the 70 supply of fuel-oil is contained under pressure.

The heating element *e* of the generator consists of a trough-like elongate body having channels as *f* on either side for containing asbestos to be saturated with alcohol for first starting the burner. The heating element *e* is aligned with the coils of the generator *c*. The central longitudinal part *e'* of the heating element is arranged to form 80 a gas chamber as shown in Fig. 4. The bottom of this gas chamber is closed by a plate *g* shown in Fig. 7. The top of the chambered portion of the heating element is provided with a plurality of transverse slits *h* 85 as shown more clearly in Fig. 6, but that portion of said top directly opposite the point of entrance of the gas mixture from the conduit *a* is left unslotted, and solid as at *i*, thereby causing the flow of gas from the 90 conduit to be divided, and to be uniformly distributing throughout both ends of said heating element.

The conduit *a* is connected with the heater *e* by an elbow *j* as shown in Figs. 2 and 4. 95 The top of the elbow *j* is flat as at *j'*, (see Figs. 4 and 7) and the bottom plate *g* of the heating element is provided with transverse slits *h* through which extend screw bolts *l*. This arrangement is provided to permit the 100 adjustment of the heating element so as to bring it properly in alinement with the generator *c*. The heating element is secured in place by bolts *m*.

The bottom of the air-and-gas mixing 105 chamber *b* is controlled by a valve *n* adjust-

able by a rod o ; the valve being preferably so arranged as to admit some air at all times; in other words, so that it cannot be entirely closed, and thus always admitting 5 some air.

The top of the mixing chamber e is closed by a cover b' .

p and p' represent the burner-heads. They consist of a hollow body provided with 10 a peripheral flange r on which is seated a ring s provided with horizontal circumferential slits t ; and integral transverse bars u extend across the slotted portion, thus making the ring a one piece construction.

15 On the open top of the hollow body of the burner-head is secured a slotted plate v . This plate is preferably constructed as shown in Fig. 5. The plate is made with a perimetric perpendicular flange w , and the 20 plate portion above said flange is provided with parallel slits x .

The plate is also made with perforated ears y through which extend the bolts z . Across the bottom slotted portion of the 25 plate v , extends an integral bar 2 , which serves to prevent the plate from warping.

Over the slotted plate v there is supported on the burner-head, a dome 3 .

When the dome 3 is in place, the gas will 30 be compelled to issue through the slits t on the side of the burner-head. The burner is used in this way for heating up the stove. But when a cooking utensil is to be quickly heated by the direct application of the flame, 35 then the dome 3 is removed so that the gas may issue through the slits x of the plate v and burn a vertical flame.

I claim:

40 1. In an oil burner of the type referred to, a burner-head comprising a hollow body provided with horizontal circumferentially extending slits, a plate fastened across the open top of the hollow body, such plate having a perimetric perpendicular flange, being 45 provided with parallel slits above such flange, a dome or cap removably seated on the hollow body over said slotted plate, thereby compelling the gas to issue from said circumferential slits of the burner- 50 body.

2. In an oil burner of the type referred to, a burner-head comprising a hollow body

provided with horizontal circumferentially extending slits, a plate fastened across the open top of the hollow body, such plate having a perimetric perpendicular flange, being provided with parallel slits above such flange, and having an integral reinforcing bar extending transversely to the slits along the bottom of the plate, centrally between 55 opposite flanges thereof, a dome or cap removably seated on the hollow body over said slotted plate, thereby compelling the gas to issue from said circumferential slits of the burner-body.

3. In an oil burner of the type referred to, a burner head comprising a vertical hollow body, having an annular exterior chamber, open at the top, and inclosed by a circumferential slotted wall, a slotted plate closing the 70 top of the hollow of said body, and a dome, or cap, removably seated on said wall, over said slotted plate and constituting a closure for the open top of said annular chamber, whereby when said cap is in place the gas is caused to issue from said circumferential slits in the wall of said annular chamber, and thus to produce a circular flame, and when said cap is removed the gas is permitted 75 to flow directly through said slits of the 80 slotted plate, and thus produce a vertical flame.

4. In an oil burner of the type referred to, a burner head comprising a vertical hollow body, said hollow body provided with a peripheral flange, a ring seated on such flange, such ring constituting a wall inclosing an annular space about said body, and having horizontal circumferentially extending slits, a slotted plate closing the top of 85 the hollow of said body, and a dome, or cap, removably seated on said ring, over said slotted plate and constituting a closure for the open top of said annular chamber, whereby when said cap is in place the gas is caused to issue from said circumferential slits in the wall of said annular chamber, and thus to produce a circular flame, and when said cap is removed the gas is permitted 90 to flow directly through said slits of the 95 slotted plate, and thus produce a vertical flame.

HARRY W. MANNING.
